PLLC(57) **CLAIM**

The ornamental design for a retainer adapter assembly, as shown and described.

DESCRIPTION

FIG. 1 is a front right perspective view of an embodiment of a retainer adapter assembly showing our new design;
FIG. 2 is a front elevation view thereof;
FIG. 3 is a rear elevation view thereof;
FIG. 4 is a left side view thereof;
FIG. 5 is a right side view thereof;
FIG. 6 is a top plan view thereof; and,
FIG. 7 is a bottom plan view thereof.

The broken lines shown in the drawings illustrate portions of the retainer adapter assembly that form no part of the claimed design.
